UNITED STATES PATENT OFFICE.

GEORGE KETTLE, OF DENVER, COLORADO.

APPARATUS FOR SEPARATING GOLD FROM SAND.

Application filed January 3, 1928. Serial No. 244,086.

This invention relates to improvements in devices for recovering fine gold from auriferous sands.

In many parts of the world and especially in parts of the United States gold occurs in great quantities mixed with sand or gravel. Much of this gold, however, is of the kind known as flour gold, and is so fine that it has been found practically impossible to separate this gold from the sand and gravel by ordinary means.

I am aware that many attempts have been made to produce special apparatus for the recovery of flour gold. But so far as I am aware, no apparatus of this nature has been found completely satisfactory.

It is the object of this invention to produce a simple apparatus by means of which flour gold can be recovered from sand and gravel, and which shall be of a simple and substantial construction, which can be manufactured without excessive cost.

This invention briefly described consists in a mechanical sluice box whose bottom is covered with coarse rough tree bark and which is also provided with a plurality of rolls arranged in parallel relation throughout the length of the box. These rolls have their outer surfaces covered with rough coarse tree bark in the same manner as the bottom of the sluice box. Means is also provided for rotating the rollers. The sand containing the flour gold after first having been passed through a screening device, and then over a concentrating table, is deposited in one end of the sluice box mixed with water. The water and sand together with the gold contained therein, is then caused to pass from one end of the sluice box to the other and to be agitated by means of the rotating rollers. The fine gold is found to adhere to the pieces of bark and after the apparatus has been in operation for some time, the bark is removed and subjected to a treatment for the recovery of the gold. The sluice box and the rolls are then covered with new bark and the machine is ready for another run.

Having thus briefly described the invention, I will now proceed to describe the same in detail, and reference for this purpose will be had to the accompanying drawing, in which the preferred construction has been illustrated and in which:

Fig. 1 is a perspective view showing an

assembly of which my improved sluice box forms a part:

Fig. 2 is a top plan view of a portion of the sluice box with parts broken away so as to better disclose the construction; 60

Fig. 3 is a section taken on line 3—3, Fig. 2; and

Fig. 4 is a section taken on line 4—4, Fig. 3.

In the drawing numeral 1 represents my 65 improved sluice box as a whole. This box has a bottom 2, sides 3, 3 and end members 4 and 5. The interior of the box is preferably provided with a metal lining 6. The end 5 is provided with a notch 7, through 70 which the water escapes during the operation of the device. A plurality of transverse members 8 extend across the lower side of the bottom 2 and attached to the ends of these members are the legs 9 on which the 75 box is supported. A plurality of rolls 10 are mounted on shafts 11 which are journaled in bearings in the side members 3, 3 in the manner shown in Fig. 4. These shafts are provided with worm wheels 12 which 80 are engaged by worms 13 on the shaft 14. Shaft 14 is journaled in bearings 15 and is provided at one end with a pulley 16 to which power is transmitted from the motor 17 by means of a belt 18. When the motor 85 operates, the rolls are rotated in a clockwise direction (Fig. 1). Secured to the bottom of the sluice box are narrow sections 19 of rough coarse bark, such, for example as the bark from oak or chestnut trees, or in fact 90 any tree bark having a rough outer surface. These bark sections are spaced a short distance apart and are placed with their rough surface uppermost. Similar bark sections 20 are secured to the outside of the rollers with 95 their rough surfaces to the outside in the manner shown quite clearly in Fig. 3.

When my improved sluice box is to be used, it preferably forms one element of an assembly such as that illustrated in Fig. 1. 100 In this assembly numeral 21 represents a hopper that is supported on suitable supports 22. A spout 23 extends from the bottom of the hopper into the upper end of a rotary screen 24. Located underneath 105 this screen is a trough 25 which terminates in a spout 26. A trough 27 has one end projecting under the open lower end of the rotary screen and serves to catch and carry away the coarser parts of the material. The 110

fine sand containing the gold passes through the screen and into the trough 25 and thence through spout 26 into the distribution chamber 28 of the concentrating table 29. Table 29 may be any one of the ordinary concentrating tables and has been shown as connected by means of rods 30 to the eccentrics 31 on shaft 32. During the operation the screen 24 and shaft 32 are rotated by suitable means not shown. The concentrates from table 29 are deposited in the end of the box 1 near the end member 4 and pass from thence underneath the rollers where the pulp is subjected to agitation with the result that the fine gold comes into contact with rough bark surface and adheres to it, while the pulp continues on its way and is finally discharged at end 5 through the notch 7.

The operation of the machine is continued for some time and then as above explained the bark is removed from the bottom of the sluice box and from the roll and either burned or subjected to a chemical treatment for the purpose of recovering the gold.

The use of rough bark in the manner above described is believed to be entirely new in this art and it is my intention to claim this as broadly as possible for it is evident that the same inventive idea can be used in connection with specifically different constructions, and therefore the specific embodiment illustrated is merely intended to serve as one example of an apparatus to which my invention has been applied.

Having described my invention what is claimed as new is:

1. An apparatus for the separation of gold from a pulp consisting of gold bearing sand and water, comprising in combination

a box whose bottom is formed by rough bark and means for agitating the pulp in contact with the upper surface of said bottom.

2. An apparatus for separating gold from a pulp consisting of gold bearing sand and water, comprising, in combination, a sluice box whose bottom is provided with a lining of rough tree bark so placed that the rough surface is on top, a plurality of rollers located above the bark lining and means for rotating the rollers.

3. An apparatus of the class described comprising, in combination, a sluice box whose bottom is provided with a lining comprising a plurality of sections of rough tree bark whose rough surfaces are uppermost, a plurality of rollers arranged in parallel relation above the bark lining, said rollers having their outer surfaces covered with rough tree bark whose rough surface is to the outside and means for rotating the rollers.

4. An apparatus of the class described comprising, in combination, an elongated sluice box having a bottom, spaced parallel sides and end members, a sheet metal covering for the upper surface of the bottom, a layer of coarse rough tree bark secured to the upper surface of the bottom with the rough surface uppermost, a plurality of spaced parallel rollers extending transversely of the box, said rollers having a layer of rough bark secured to their outer surfaces the rough surface of the bark being on the outside and means for rotating the rollers.

In testimony whereof I affix my signature.
GEORGE KETTLE.
